(57) **CLAIM**

The ornamental design for a faucet, as shown and described.

DESCRIPTION

FIG. 1 is a perspective view of a faucet showing my design;
 FIG. 2 is a front elevation view;
 FIG. 3 is a rear elevation view;
 FIG. 4 is a right side elevation view;
 FIG. 5 is a left side elevation view;
 FIG. 6 is a top plan view; and,
 FIG. 7 is a bottom plan view.

The broken-line disclosures in the view represents portions of the faucet in which the claimed design is embodied, but which forms no part of the claimed design.
